UNITED STATES PATENT OFFICE.

JOHN W. BURKETT, OF KANSAS CITY, KANSAS, ASSIGNOR TO THE KANSAS CITY HAY PRESS COMPANY, A CORPORATION OF MISSOURI.

BALING-PRESS.

1,017,133.

Specification of Letters Patent. Patented Feb. 13, 1912.

Application filed August 24, 1910. Serial No. 578,722.

To all whom it may concern:

Be it known that I, JOHN W. BURKETT, a citizen of the United States of America, residing at Kansas City, in the county of Wyandotte and State of Kansas, have invented certain new and useful Improvements in Baling-Presses; and I do hereby declare that the following is a full, clear, and exact description of the invention, such as will 5 enable others to make and use the same, reference being had to the accompanying drawings, forming a part of this specification.

The objects of the invention are: first, in a continuous power press to control the opening and closing of the feed opening, and secondly to govern the reciprocation of the rack operating the plunger.

The invention consists in the novel construction and combination of parts, such 20 as will be first fully described and then specifically pointed out in the claims.

In the drawings: Figure 1. is an isometric view of a baling press, embodying the invention. Fig. 2. is a plan of the same. Fig. 25 3. is a vertical, sectional view, taken on the lines *x*, *x*, on Fig. 2, showing the positions of the operative parts at the respective ends of the head block movement. Fig. 4. is a transverse, vertical, sectional view, enlarged, 30 taken on the line *y*, *y*, on Fig. 2, looking rearwardly. Fig. 5. is an enlarged, isometric view, in detail, of the large sprocket wheel and spur wheels and the supports for the shaft carrying said wheels, also showing 35 portions of the upper and lower angle beams adjacent thereto. Fig. 6. is a detail view of portions of the large sprocket wheels and rack bars, the spur wheels and portions of the upper and lower beams showing opera- 40 tive positions of the rack bars. Fig. 7. is a detail view, in perspective, of the head block and rack bars.

Similar numerals of reference indicate corresponding parts in all the figures of the 45 drawings.

With reference particularly to the drawings, the bed of the baling press consists of the angle beams 10, 10, which are arranged

in a parallel position and the requisite distance apart for the formation of the bale. 50 These beams extend the full length of the press, and have the grooves formed by the angles of the beams facing inwardly.

With the lower surface and forward ends of the beams 10, are connected the ends of a 55 transverse supporting plate 12, which is bent between said ends in a downwardly-curved line, and bears upon the upper surface of the forward axle 14. Through the plate 12 and the axle extends the king bolt 15. Upon 60 the ends of the axle are mounted the forward wheels 16.

At a point distant from the forward axle 14, rearwardly and approximately two-thirds the distance toward the rear ends of 65 beams 10, is positioned the rear axle 17, which is bolted transversely to the lower surface of said beams. Upon the ends of said axle are the wheels 18, which are slightly larger in circumference than the forward 70 wheels 16. Above the beams 10 are the longitudinally-extended angle beams 20, the grooves formed by the angles or surfaces of the beams facing outwardly, the downwardly-extending portion of the beams 20 75 being in vertical lines with the upwardly-extending portions of angle beams 10. These beams 20 are parallel with the beams 10, and at an approximate distance in height from the beam 10 to the distance allotted between said beams 10, and extend in length from a point in a vertical line with the rear ends of beams 10, to a point in the direction of the forward ends of beams 10 80 approximately two-thirds the length of said 85 beams.

The upper beams are secured in a horizontal position by the vertical side plates 21, which form the sides to the baling chamber 21^x, and are bolted to the inner surfaces 90 of the upwardly-extended portions of angle beams 10, and the outer surfaces of the downwardly-extending portions of beams 20. These plates 21 extend from a point about two-thirds the distance forwardly of 95 the rear ends of beams 10, the proper dis-

tance to afford a large feed-opening 21° , or to a point nearly intermediate the ends of beams 10, the space between the rear ends of beams 10 and 20, in rear of the feed chamber constituting the baling chamber 20^x. The bottom of the feed and baling chambers consists of a wide plate 22, extending from the line of the forward ends of the plates 21, and from the inner surface of one plate 21, to the inner surface of the opposite plate 21, and also in length to a point in line with the rear ends of beams 10.

23 indicates the top to the baling chamber, which consists of a plate extending in width from the vertical line of the outer edge of one of the horizontal portions of the angle beams 20, to a like point on the other angle beam 20, and in length from a point in a vertical line with the rear ends of beams 20, to a point a short distance forwardly of the vertical lines of the rear ends of the side plates 21, to the feed chamber 21^x.

Within the baling chamber is a rocking plunger or head block 24, for compressing the material to be baled. The head block consists of a hollow casting, the sides 24^x, of which are in vertical lines with and a slight distance from the vertical, inner surfaces of the sides 21, of the feed chamber. The top 24° , of the casting or head block is inclined rearwardly and downwardly, and is connected integrally with the sides 24^x, and the vertical plates 25, which constitutes the compression face of the head block. The head block is mounted on the wheels 26, the journals 27 for which are secured to the inner surfaces and lower, forward portions of the sides 24^x, which portions of the sides are slightly inclined upwardly and forwardly to the line of the face 25, so that in a movement rearwardly of the head block the lower surface of the face 25 comes into a close position with the upper surface of the plate 22, in the bottom of the feed chamber, and the forward portion of the inclined top 24° approaches quite closely to the line of the lower surface of the forward end of the top-plate 23, which is as seen the rear end of the feed opening 21° , in its reciprocating movements. In the outer surfaces of the sides 24^x, of the head block, at points about equi-distant from the rear portion of the top-plate 24^x, and the journals 27, for the wheels 26, are horizontal recesses 28, in which are seated the rear ends of the flat rack bars 30, these bars being secured in the recesses by means of the bolts 29, extending through said bars, and the sides 24^x, of the head block (see Fig. 7). Upon the outer surfaces of these bars adjacent to their forward ends, are rigidly secured the stop pins 31.

At a point a short distance forward of the

line of the forward ends of the side-plates 21, to the feed chamber are the rearwardly-curved guide plates 32, arranged in a vertical position and in the path of movement of the studs 31, on the rack bars 30, these guide plates 32 being positioned in such a manner that when the head block is in a position at the rear end of the feed chamber and at the end of the head block movement for compressing the baling material in the baling chamber the studs 31, on the rack bars 30, are in contact with the curved guide plates 32. These guide plates are secured at their upper ends to the lower surfaces of outwardly-extended portions of angle beams 20, and at their lower ends to the outer surfaces of the upwardly-extended portions of the beams 10.

With the upper surfaces of the inwardly-extended portions of the angle beams 10, at a point in a vertical line with the forward ends of the angle beams 20, are rigidly connected by the bolts 33^x, the forwardly curved guide plate 33, the upper end of which plate is secured rigidly by the bolts 33^x to the upper surface of a transverse cleat 34, secured at its ends to the upper surfaces and forward ends of beams 20. These guide plates 33 are in the path of the forward ends of the rack bars 30, and come into contact therewith at the end of their forward head block movement. In the upwardly-extended portions of the angle beams 10, transversely to the point of attachment of the lower ends of guide plates 33, is a groove 10° , of the proper depth and length, in which the stop pins 31, on the forward ends of the rack bars 30, enter in the beginning of a rearward movement of the head block.

To the lower surfaces of the angle beams 20, intermediate vertical lines extending through the forward ends of the sides 21, of the baling chamber and the forward ends of beams 20, is secured rigidly the outer ends of the short horizontal studs 35, which are spaced apart a short distance from each other.

To the inner surfaces of the upwardly-extended portions of the beams 10, in a vertical line with the studs 35, are connected rigidly the outer ends of the short, horizontally-extended lugs 36. The inner ends of these lugs 35 and 36 are connected, respectively, with the outer surfaces and upper ends of the parallel shaft-bearing plates 37, which are spaced apart a short distance from each other. In the said plates, at a point equi-distant from their upper and lower ends and from vertical lines extending through the said plate at the point of connection of the lugs 35 and 36 is journaled a transverse rotary shaft 37^x, the ends

of which shaft extend a short distance outwardly from the lines of the outer surfaces of said bearing plates. On the shaft 37^x, between the bearing plates 37, is fixedly mounted a large sprocket wheel 38, and upon the outer ends of said shaft are fixedly mounted the spur wheels 40. The ends of plates 37, extend both forwardly and rearwardly of the main portion of the plates, such end having its upper and lower surfaces inclined toward a point horizontally in line with and bisecting the axis of shaft 37^x, the plates being in the form of a diamond. With the outer ends of these plates are connected the bolts 37^x.

With the outer surfaces of the plates 37, between the studs 35, are rigidly connected the inner ends of the horizontally-extended studs 46^x, upon the outer ends of which 20 studs, adjacent to beams 20, are journaled the upper guide rollers 46, these rollers being in the path of the rack bars in their highest plane of movement, and with the lower portions of said plates 37 are rigidly connected the inner ends of the studs 47^x, upon the outer ends of which studs are journaled the lower guide rollers 47, these rollers being positioned in a vertical line with the rollers 46, and in the path of the rack 25 bars 30, in their lowest plane of movement. Upon the inner surfaces of the rack bars 30 are secured a series of studs 41, beginning at a point adjacent to the forward ends of the rack bars a distance corresponding to 30 the position of stud 31, and in regular order in the direction of the rear ends of said bars, these studs being of the requisite number, spaced apart a distance corresponding to the width of the teeth or spurs of the 35 spur wheels 40, and in number sufficient to carry the rack bars to a position in which the forward ends of the bars come into contact with the upper portion of the forward, curved guide-plate 33, in which position of 40 the rack bars 30, the last stud in the direction of the rear ends of the rack bars is engaged by the spur wheels, to move said studs in an arc of a circle, while the forward ends of the rack bars are moving in 45 the arc of a circle in contact with the guide plate 33, downwardly to a position shown in dotted lines in Fig. 3, in contact with the lower guide rollers 47, and moving rearwardly to move the head block in a corresponding direction.

The number of studs 41, shown on the inner surface of the rack bars are seven, and the spurs on the spur wheels are five in number, which number may be varied as 50 the condition requires. These studs 41 extend to a position about one-half the distance from the forward toward the rear ends of said rack bars, and with the spur wheels

and guides act as a mangle rack to communicate a reciprocating movement to the 65 head block.

Upon the upper, horizontal surfaces of the inwardly-extended portions of the angle beams 10, at points a short distance forwardly of the guide plates 33, are secured 70 the journal boxes 48, in which is journaled a transverse, rotary power shaft 49, upon which shaft, intermediate the journal boxes 48, is fixedly mounted the small sprocket wheel 50. Over this sprocket wheel extends an 75 endless sprocket chain 51, which also extends to and over the large sprocket wheel 38, on shaft 37^x.

The end of shaft 49, on the left-hand side of the machine, extends a short distance 80 outwardly from the line of the outer surface of the journal boxes 48, and upon said end of the shaft is mounted a large gear wheel 52.

The continuous power of the press is obtained from a gas engine 54, the base 55 of which is secured to the upper surfaces and forward ends of the inwardly-extended portions of the angle beams 10. The rear portion of the base extends forwardly to within 90 a short distance of the journal boxes 48, and upon the rear, upper, horizontal surfaces of the base is journaled in the journal boxes 56, a transverse, rotary power shaft 57. The end of said shaft on the right and 95 left-hand side of the baling press extends a short distance beyond the line of the journal boxes, and upon said end of the shaft are mounted the large balance wheels 58. Upon the said shaft 57, in line with the 100 gear wheel 52, is a small gear wheel 60, with which said gear wheel 52 is in mesh, and by means of which power is transmitted from the engine to the power shaft 49. The portion of the shaft 57, between the 105 journal boxes 56, is in two parts, and upon said parts are the separate crank wheels 62, connected by a crank pin 63, with which pin is connected pivotally the outer end of the pitman 64, of the gas engine 54. The 110 gas engine shown is of the usual type, not requiring illustration or further description, other power being employed when found convenient to the operation of the press.

The automatic feeder for feeding the baling material through the feed-opening 21° into the feed-chamber 21^x consists of a rocking beam, of considerable length, which is secured by the clamping rods 66, to the flanges 67^x, on the upper portion or angle 120 of a triangular plate 67, which plate is secured rigidly at the apex to a rock shaft 68. The shaft 68 is journaled at its ends in the arch plates 69, on the upper ends of the rods or standards 69°, 69^x, these rods on the 125 respective sides of the baling press being in

pairs and spaced apart at an angle to each other. The forward standards or rods 69° at their lower end are bent at right angles and flattened, and bear on the upper surfaces of the cleats 34, and are secured by the bolts 34^x, which pass through the flattened lower ends of the rods 69°, the outer ends of the cleats 34, and the horizontal portion of beams 20. The rods 69° are also flattened at their lower ends, and secured by bolts 70 to the upper surfaces of the horizontal portions of the angle beams 20, at a point a short distance in rear of the vertical lines passing through the forward ends of the sides 21, of the baling chamber.

The upper end of the beam 65 extends in its normal position upwardly and rearwardly to its full elevation above and in a vertical line with the rear portion of the baling chamber, and upon the forward surface of said end are lugs 65^x.

71 indicates the feeding arm, which is provided with lugs 72, on its inner surface and upper end pivotally connected with the lugs 65^x, on the rocking beam 65. At a point on the arm 71, a short distance below the lugs 72, is a transverse bolt 73, with the ends of which bolt are connected pivotally the upper ends of the rods 74, which hold the arm 71 normally at an acute angle to the beam 65, and directed toward a line extending vertically through the central portion of the feed chamber, the lower ends of the rods being pivotally connected with the rear surfaces 35 of the arch plates 69.

Upon the forward surface and lower end of the feed arm 71 is rigidly connected a block 75. Upon the outer surfaces and lower ends of the arm 71 and block 75 are flat feed-40 plates 76, upon the lower end portions of which plates are teeth 77, for drawing upon the baling material.

As heretofore described, the feeder is of well-known construction, and is employed in feeding the material to the ordinary baling press.

80 indicates the apron for preventing the baling material from entering the feed chamber behind the head block, when moving rearwardly to compress the material. This apron consists of a rigid material, such as metal plate of nearly the same width as the space between the sides 24^x, of the head block, and in length is about equal to the length of the sides 21, of the feed chamber. Through the sides 24^x, of the head block, near the inner surface of the top 24°, is a transverse rod 81, around which rod is extended the rear end of apron 80. The guides 60 of the apron 80 consist of channel bars 82, connected rigidly to supports 82^x secured to the angle beams 20, said channel beams being adjacent to the inner surfaces of the

standards or rods 69°, 69^x, for the rock shaft 65, and which are inclined rearwardly and downwardly to a position in a vertical line with the forward ends of the sides 21, of the feed chamber, the grooves 83 being opposite each other.

Upon the ends of a transverse rod 84, are 70 rollers 85, loosely mounted thereon, and which rollers have a sliding bearing on the lower surfaces of the respective grooves 83. Around the rod 84, between the rollers are extended portions of the forward end of the 75 apron 80, which telescope within the guides 83. With the ends of rod 84, between the apron and the rollers is pivotally connected the lower forked end of the timing lever arm 86, the upper end of which arm is forked 80 and extended inwardly and pivotally connected with the ends of the bolt 87, extending through the lower portion and end of the triangular plate 67.

Upon the upper surfaces of the horizontal 85 portions of the beams 20 are transverse boards 88, extending over the feed chamber at the forward end of the top plate 23, and also a short distance in rear of a vertical line passing through the forward ends of 90 the sides 21, of the feed chamber. Upon the upper edges of these boards, which are set edgewise in position, is connected a frame 90, having a centrally-located, rectangular opening 91, of the same width as 95 the feed-opening 21°, to the feed chamber 21^x. With the inner, longitudinal sides to the opening 91, are connected the downwardly-extended plates 92.

Upon the upper surface of the frame 90, 100 on the left-hand side of the machine, is an upwardly-extended, material-guiding plate 93, having a lower, flanged portion 94, secured to the upper surface of the frame 90 and extending nearly the length of said 105 frame. The plate 93 extends upwardly a considerable distance, and upon the forward end of the frame is a vertical, transverse plate 95, the same height as the plate 93, and which is provided with a flange 96, secured to the upper surface of frame 90, the two plates being connected at their adjacent ends. In the forward, transverse plate 95 are slots 97, which permit the rods 74 on the feeder arm 71 to enter in the rocking movement of the beam 65.

To the upper surface of frame 90, a short distance from the inner surface of the plate 93, are connected rigidly the lower ends of the rack teeth or rods 98, which are arranged 120 a short distance apart in a parallel plane with plate 93, to form a rack, and extend upwardly a slight distance above the plane of the upper portion of said plate 93, which forms a back to the rack teeth. The teeth 125 or rods set out from the plate 93 about one-

half the length of the teeth of an ordinary hay fork. 99 indicates a block, at the forward ends of the opening 91, in the frame 90, secured to the inner surface of plate 95, 5 and extending downwardly as far as the plate 92, thus serving to direct the baling material into the opening in the baling chamber. The upper surface of the block 99 is inclined downwardly and rearwardly, 10 for assisting the passage of the baling material.

100 indicates the dumping frame for the division boards, which is hinged to the rear end of the opening 91, in the frame 90, and 15 is provided with the handles 101, for raising the frame 100. The frame 100 is of well-known construction, and enables the deposit of the division board without danger to the operator of the press. The tension device 20 at the rear end of the baling chamber, which is also of well-known construction, consists of the rod 102, passing beneath the beams 10, and upwardly through the outwardly-extended portions of beams 20, and the ends 25 of the plate 103, the ends of the rod being screw-threaded. The tension is obtained by the adjustment of the wheels 104 whose hubs are screw-threaded and engage the screw-threaded ends of rod 102.

30 In operation, power from the engine is transmitted from the plunger rod 64, to the crank shaft 57, thence from the small gear 60, on said shaft, to the large gear wheel 52, on shaft 49, thence from the sprocket 35 wheel 50, on said shaft to the sprocket chain 51, thence from the sprocket chain to the large sprocket wheel 38, on shaft 37, and from the spur gear wheels 40, on said shaft, to the rack bars 30, operating the head block 40 24, and a reciprocating movement is imparted to the head block 24. In these reciprocating movements of the head block the studs 41, on the rack bars are constantly in engagement with the spur wheels 40, and in 45 moving rearwardly the rack bars are guided by the lower rollers 47, to a point in which the head block reaches the end of the inward movement, at which point the stop pins 31, on the outer surface and forward ends of 50 the rack bars, come into contact with the lower portion of the guiding plate 33, and in continuance with the movement of the spur wheels the studs are caused to move on said curved surface upwardly, the last stud 55 41, on the forward ends of the rack bars, being at the same time in engagement with and between the spurs of the wheels. In this movement the forward ends of the rack bars are raised in an inclined position, and 60 brought into contact with the upper guide wheels 46, and consequently rocking the head block on its wheels 26, and bringing the face portion from its inclined position,

as seen in Fig. 3, into a perpendicular position, and the lower portion of the face portion 25. In the forward movement of the rack bars in contact with the guide rollers 46, the ends of the rack bars come into contact with the upper portion of the curved guide plate 33, at which moment the last 70 studs 41, in the series on the rack bars are within the spurs of the spur wheel 40, and consequently the rack bars move downwardly, guided by the curved surface of the guide plate 33, when the rack bars come 75 into position upon the lower guide rollers 47, and the spur wheels engage with each one of the studs 41, on the rack bars, and the head block 24 moves rearwardly, this operation being repeated, and as rapidly as 80 the power is applied. The constant supply of the baling material to the feed chamber 21^x is made during the reciprocation of the head block 24, and at the time subsequent to the completion of its rearward movement 85 to compress the material within the baling chamber, and a movement of the head block toward the forward end of the feed chamber, approximately one-half the distance toward the forward end of the feed chamber, 90 or during the movement of the timing lever arms 86, from their rearwardly-inclined position, as seen in Fig. 1, to a forwardly-inclined position seen in dotted lines in Fig. 3, in which the roller 84 has moved about 95 one-half the distance in the direction of the forward end of the channel guide-plates 82 and the feeder beam 65 obtains a dwell sufficient in length of time to enable the feeding of the baling material within the feed 100 opening. At the incipiency of this movement of the head block the beam 65 is given an upward movement, in a slight degree, and upon the change of position of the arms 86, in which the dwell of the beam 65 takes 105 place, the said beam 65 moves downwardly a like distance. During this time in which the head block is completing its forward movement, described, the bundle of baling material raised by the hand fork is thrown 110 upon the table 90 and the bundle falls across the opening 91, and as the head block moves forwardly, the power of the head block is transmitted through the apron 80, to the pivoted lever arms 86, which now act first 115 to produce a dwell of the feeder beam as before described and then to draw upon the plate 67 and beam 65, and as apron 80 moves within the guides 83, the feeding arm 71 moves downwardly with a quick movement, 120 into the feed chamber of the baling press, the teeth 77 drawing the material into the feed chamber, in rear of the head block. The head block 24 having reached the end of its forward movement and begun its rearward movement, the apron 80 acts upon the 125

lever arms 86, and the beam 65, as before described, in changing their operative positions, and as the head block 24 moves rearwardly in the baling chamber it compresses 5 the material, the apron closes the space in the feed chamber behind the head block, and thus prevents admission of the material. The charges or bundles of material are repeatedly delivered to the feed chamber, as usual in baling, until the baling chamber contains an amount equivalent to 10 form a bale, and upon the return movement of the head block, a division board (not shown) is placed upon the dumping board 15 100, and dropped into the baling chamber in the usual manner.

In pitching the material to be baled across the opening 91, in the table 90, the rack 98 acts as a guide to the bundles, and at the 20 same time the tines of the fork which compress the material against the wires 98, are enabled to be quickly withdrawn from the bundles as the tines are given space in which to project, in rear of the wires 98, the 25 plate 93 holding in check any material passing said wires. The rapid movement of the head block obviously requires the material to be supplied with considerable speed, the head block in each forward movement removing any loose material accidentally falling into the feed chamber in its rearward movement, and this is discharged from the forward end of the baling chamber. The 30 resistance to the compression of the material in the baling chamber is controlled by the usual compression devices 102 and 103.

I am aware that mangle racks have been employed in baling presses to actuate the plunger. In my construction the rack bars 40 are rigidly connected with the plunger and the reversals of movement are made conjointly with the rocking movement of the plunger while the reciprocating movement of the rack is completed between opposed 45 curved guide plates with which the stop pins on the rack bars and the ends of the bars alternately come into contact.

Various changes in the construction of the invention may be made, within the scope 50 of the appended claims, without departing from the spirit of the invention.

Having fully described my invention, what I now claim as new and desire to secure by Letters Patent is:

55 1. In a baling press the combination with the feed chamber for the material to be baled having a feed opening, a reciprocating head block or plunger within said chamber, means for operating said plunger, a rigid apron flexibly connected with the plunger and adapted to close the feed opening 60 suitable guide bearings for said apron and a rock shaft on said press, a material

feeding beam and a triangular plate on the rock shaft supporting said beam and an 65 operative timing lever arm pivotally connected with one angle of the said triangular plate and the said apron adapted to afford a dwell of said material feeding beam during a partial forward and backward movement of the plunger.

2. In a baling press the combination with the feed chamber for the material to be baled having a feed opening a reciprocating head block or plunger within said chamber, means 75 for operating said plunger and rocking material feeding devices on the said press for feeding the material within the feed chamber consisting of standards a rock shaft mounted thereon, a triangular plate secured 80 rigidly at its apex to said shaft, a rocking beam connected at its lower end with the upper portion or angle of the said triangular plate, a feeding arm pivotally connected with the upper end of said beam and connecting rods pivotally connected with said arm and the standards supporting the rock shaft a rigid apron flexibly connected at its forward end with the plunger, and movable in suitable guide bearings in rear of the feed 85 chamber, and an operative timing lever pivotally connected with the rear end of said apron and the lower portion or angle of the said triangular plate on the rock shaft and adapted to afford a dwell of the material feeding beam during a partial forward and backward movement of the plunger.

3. In a baling press the combination with the feed chamber the plunger, rack bars 100 rigidly connected therewith and parallel shaft bearing plates between said rack bars, a power driven rotary shaft journaled in said plates whose ends extend beyond the lines of their outer surfaces, spur wheels on 105 the said ends of said shaft, studs on the inner surfaces of the rack bars spaced apart upper and lower guide rollers for the rack bars and curved guide plates co-acting with the outer ends of the rack bars when 110 reversed in position by the spur wheels, and stop pins on the outer surfaces and ends of the rack bars.

4. The combination in a baling press with the bed the feed chamber for the material to be baled the head block or plunger 115 of rack bars rigidly connected with the plunger, parallel shaft bearing plates located between the rack bars and supported in position adjacent to the rear end of the feed chamber, a power driven rotary shaft journaled in said bearing plates, its ends extending beyond the lines of the outer surfaces thereof, spur wheels on the ends of said shaft, studs on the inner surfaces of the 120 rack bars extending from the outer ends of

the rack bars toward the plunger in series and spaced apart for engagement with the spur wheels and stop-pins on the outer surfaces and at the outer ends of said rack bars 5 rear curved guide plates supported in position in rear of the feed chamber and at the end of the rearward movement of said rack bars and with which the ends of the rack bars come into contact when the inner stud 10 of the series is engaged by the spur wheels to reverse the direction of movement of the

rack bars, upper and lower guide rollers in the upper and lower horizontal planes of movement of the rack bars.

In witness whereof, I have signed this 15 specification in the presence of two subscribing witnesses, this 9th day of August, 1910.

JOHN W. BURKETT.
